CLAIM

The ornamental design for a seat, as shown and described.

DESCRIPTION

FIG. 1 is a perspective view of a seat showing my new design in the form of a chair;

FIG. 2 is a front elevational view;

FIG. 3 is a left side elevational view, the right side being a mirror image thereof;

FIG. 4 is a rear elevational view;

FIG. 5 is a left side perspective view of a seat showing my new design in the form of a loveseat, the right side being a mirror image thereof;

FIG. 6 is a front elevational view of FIG. 5; and,

FIG. 7 is a rear elevational view of FIG. 5.

FIG. 5

FIG. 6

FIG. 7
